CABLE DEVICE

Filed July 17, 1930

FIG. 4

WITNESS:

H. S. Henderson

By

George G. Allenbaugh Inventor

Gause

Attorney

UNITED STATES PATENT OFFICE

GEORGE G. ALLENBAUGH, OF MANSFIELD, OHIO, ASSIGNOR TO THE OHIO BRASS COMPANY, OF MANSFIELD, OHIO, A CORPORATION OF NEW JERSEY

CABLE DEVICE

Application filed July 17, 1930. Serial No. 468,688.

My invention relates to holding or fastening devices for cables and is particularly adapted for securing a plurality of span wires to a single point of support in insulated relation thereto.

5 The object of my invention is to provide a device which will have contained therein means for securing it to a single point of attachment on a support and connecting there-
10 to a plurality of cables and having means thereon which are adjustably secured to the device in flexible relation thereto for grip-
ping the cables.

15 My invention resides in the new and novel construction, combination and relation of the various parts hereinafter described and shown in the drawing accompanying this specification.

In the drawing:-

20 Fig. 1 is a top plan view of my invention arranged for four attachments and insulated from the point of support.

Fig. 2 is a side view in elevation of my invention shown in Fig. 1.

25 Fig. 3 is a view in partial section on the line 3—3 of Fig. 1 showing the attachment of the cable thereto.

Fig. 4 is a fragmentary view of the main fitting arranged to be attached directly to a
30 support without the intervening insulator.

In the preferred embodiment of my invention I use a body member 1 which has an arc shaped portion 2 of circular formation as shown in Fig. 3 and provided with a plurality of grooves 3 to receive the cables 4. The member 2 is hollow and open at the ends and provided with inwardly projecting and spaced ribs 5 forming an arcuate recess 6.

35 The portion 2 is provided with projecting and spaced arms 7 from the ends of the portion 2. Disposed between the ends of the arms 7 is an insulating member 8 provided with transversely spaced holes 9—9' having their axes at right angles to each other to receive the pins 10 and 11. The pin 10 passes through the insulating member 8 and the member 1 to the insulator 8 and the pin is held in position by means of the coppers 12.

40 Secured to the insulator by means of the

pin 11 is a yoke shaped member 13 having the arms 14 which are provided with registering openings to receive the pin 11 held in position by the spring coppers 15. The member 13 is provided with the eye member 16 55 and the opening 17 to receive a fastening bolt to the supporting member which may be a trolley pole.

Positioned in the arcuate groove 6 are clamping members 18 each provided with 60 a neck portion 19 and a head portion 20. The head portions fit loosely within the groove 6 and rest against the faces of the flanges 5 and are free to slide from end to end in the groove 6, but are prevented from 65 removal by means of the coppers 21. The clamps 18 are also provided with a portion 22 which is an extension of the portion 19 and is fitted with grooves to receive the cable 4 which is looped about the portion 2 and 70 rests in one of the grooves 3.

The clamps 18 are provided with a complimentary clamping member 23 which is held in position by means of bolts and nuts 24 which are positioned in registering holes in 75 the members 22 and 23. The members 22 and 23 are provided with co-operating grooves which form the channels 25 for receiving the cable 4.

The arcuate portion 2 is provided with the 80 projecting lips 26 which add to the support of the cable 4 and avoid the cable engaging with abrupt corners on the portion 2. The end of the lips 26 are spaced apart forming a slot 27 through which projects the neck portion 19 of the clamp 18.

The portion 2 may be supplied with the form of connection shown in Fig. 4 if desired in place of the arms 7 and eliminates the use of the insulator 8 at least in the combination 90 shown in Fig. 1.

The arrangement shown in Fig. 4 is provided with the arms 28 which connect to the ends of the portion 2 the same as the arms 7 and the arms are also connected to the holding portion 29 provided with an eye 30 similar to that shown as 16 and 17 respectively in Fig. 2 thus permitting the attachment of the portion 2 directly to the supporting member without the use of an insulator or an insulator 100.

may be interposed between the portion 29 and the pole support.

It will be recognized that the span wire is held in clamped relation with respect to the portion 1 by means of the flexible attachments 18 which move universally relative to the portion 2 to allow the span wires to move relative to the portion 2 and to each other or independently, freely and naturally than if the span wire was clamped rigidly to the member 2 or similar device.

It will be noted that the strain between the members 1 and 13 is taken up by the insulator 8 and the insulating material is under compression which is superior to placing it under tension and the members 10 and 11 are interlocked should the insulator be broken and fall away.

The portion 2 acts in the capacity of the ordinary type of thimble around which the cable is positioned.

Having described my invention, I claim:

1. A cable device comprising a body member having a hollowed out arcuate portion open along one side and arms projecting therefrom being spaced apart and having registering openings adjacent their ends, a yoke shaped member having arms and means of securing the yoke to a support and registering openings adjacent the ends of the arms, an insulator interposed between the arms of the said members and holding the plane of each pair of arms at right angles and the arms spaced and insulated and securing means passing through the openings of each pair of arms and through openings in the insulator to hold the members and insulator together, the arcuate portion having grooves in its outer surface opposite the side opening and a clamping member movably mounted in the hollow of the arcuate portion and projecting through the side opening to receive and clamp a cable seated in one of said grooves.

45 2. A cable device comprising a pair of arms spaced at one end and having registering openings therethrough and integrally connected at the other end by a tubular member having an opening along the side away from said arms and inwardly projecting spaced ribs within the member, clamping means mounted within the hollow of the tubular member and projecting therefrom to receive a cable and seated against the said ribs when in use and means to secure the arms to a support.

50 3. A cable device comprising a pair of arms spaced at one end and having registering openings therethrough and integrally connected at the other end by a tubular member to receive a cable looped there around and having an opening along the side away from said arms and inwardly projecting spaced ribs within the member, clamping means

member and projecting therefrom to receive and grip said cable and seated against the said ribs when in use and means to secure the arms to a support.

4. A cable device comprising a pair of arms spaced at one end and having registering openings therethrough and integrally connected at the other end by a tubular member having a plurality of spaced means along its outer surface to receive cables looped about the member and having an opening along the side away from said arms and inwardly projecting spaced ribs within the member, clamping means mounted within the hollow of the tubular member and projecting therefrom to receive said cable and seated against the said ribs when in use and means to secure the arms to a support.

5. A cable device comprising a pair of arms spaced at one end and having registering openings therethrough and integrally connected at the other end by a tubular member having an opening along the side away from said arms and inwardly projecting spaced ribs within the member, freely movable clamping means mounted within the hollow of the tubular member and projecting therefrom to receive a cable and seated against the said ribs when in use and means to secure the arms to a support.

6. A cable device comprising a pair of arms spaced at one end and having registering openings therethrough and integrally connected at the other end by a tubular member having an opening along the side away from said arms and inwardly projecting spaced ribs within the member, clamping means mounted within the hollow of the tubular member and projecting therefrom to receive a cable and seated against the said ribs when in use and means to secure the arms to a support, the said means comprising a separate member and an interposed insulator holding the member in spaced and insulated relation to the arms.

7. A cable device comprising a pair of arms spaced at one end and having registering openings therethrough and integrally connected at the other end by a tubular member having an opening along the side away from said arms and inwardly projecting spaced ribs within the member, clamping means pivotally, rotatably and slidably mounted within the hollow of the tubular member and projecting therefrom to receive a cable and seated against the said ribs when in use and means to secure the arms to a support.

8. A cable device comprising a pair of arms spaced at one end and having registering openings therethrough and integrally connected at the other end by a tubular member having an opening along the side away from said arms and inwardly projecting spaced ribs within the member, clamping

means slidably and pivotally mounted within the hollow of the tubular member and projecting therefrom to receive a cable and seated against the said ribs when in use and
5 means to secure the arms to a support.

9. A cable device comprising a pair of arms spaced at one end and having registering openings therethrough and integrally connected at the other end by a tubular member having an opening along the side away from said arms and inwardly projecting spaced ribs within the member, clamping means mounted within the hollow of the tubular member and projecting therefrom
10 to receive a cable and seated against the said ribs when in use, the projecting portion of the clamping means provided with a separately formed portion to clamp the cable and
15 means to draw the portions into clamping relation to the cable and means to secure the arms to a support.
20

In testimony whereof I affix my signature.
GEORGE G. ALLENBAUGH.
